United States Patent Office

Des. 175,541
Patented Sept. 13, 1955

175,541

BOX

Ernest J. Francis, Harrisonburg, Va.

Application December 3, 1953, Serial No. 27,878

Term of patent 14 years

(Cl. D58—12)

FIG. 1.

FIG. 2.

FIG. 3.

Fig. 1 is a perspective view of a box showing my new design.

Fig. 2 is a side elevational view thereof, showing the cover portion removed from the bottom portions thereof; and

Fig. 3 is an end elevational view thereof.

I claim:

The ornamental design for a box, as shown.
